CLAIM

The ornamental design for a computer cabinet, as shown and described.

DESCRIPTION

FIG. 1 is a perspective view of a computer cabinet in one position, according to one embodiment of this invention;

FIG. 2 is a front view of the computer cabinet, as shown in FIG. 1;

FIG. 3 is a rear view of the computer cabinet, as shown in FIG. 1;

FIG. 4 is a side view of the computer cabinet, as shown in FIG. 1;

FIG. 5 is a side view, opposite the side view shown in FIG. 4, of the computer cabinet, as shown in FIG. 1;

FIG. 6 is a top view of the computer cabinet, as shown in FIG. 1; and,

FIG. 7 is a bottom view of the computer cabinet, as shown in FIG. 1.

The broken line showing is for environmental purposes only and forms no part of the claimed design.
